UNITED STATES PATENT OFFICE.

JULIUS J. KARGES, OF KANSAS CITY, MISSOURI.

TRAY.

No. 914,285.

Specification of Letters Patent.

Patented March 2, 1909.

Application filed December 21, 1906. Serial No. 348,953.

To all whom it may concern:

Be it known that I, JULIUS J. KARGES, a citizen of the United States, residing at Kansas City, in the county of Jackson and State of Missouri, have invented certain new and useful Improvements in Trays, of which the following is a specification.

My invention relates to improvements in trays.

10 The object of my invention is to provide side and end members connected to each other so as to form the sides of a tray, a counter show case or other body forming the bottom of the tray to which the side and end members may be readily attached or detached therefrom.

20 My invention provides further detachable side and end members hinged to each other so as to be collapsed when not in use, such members being readily adapted to be placed on a show case or counter for the purpose of forming therewith a tray for holding goods.

25 My invention provides further extensible side members by which the length of the tray formed with the end members and the show case may be varied to suit circumstances.

30 My invention provides further extensible end members by which the width may be varied to suit the width of the show case or counter, one of the objects of my invention being to provide an apparatus that may be varied in dimensions to fit the place in which it is to be used.

35 My invention provides further extensible partitions which may be hinged to the side or end members so as to permit the collapsing of the apparatus into small space when not in use.

40 Other novel features, such as the releasably locking of the side and end members at angles to each other, and the releasably holding of the parts of the members from lengthwise movement relative to each other, are hereinafter fully described and claimed.

45 In the accompanying drawings, illustrating my invention, Figure 1 is a plan view of the apparatus shown mounted on a counter, part of which is shown in dotted lines. Fig. 2 is a top view of the apparatus shown collapsed. Fig. 3 is a vertical sectional view taken on the dotted line $a-b$ of Fig. 1. Fig. 4 is a horizontal sectional view taken on the dotted line $c-d$ of Fig. 3, showing the hinge connection between one of the partitions and one of the side members. Fig. 5, is an enlarged plan view, partly broken away,

and showing the connected ends of a side and end member, the members being locked at angles to each other. Fig. 6 is an enlarged vertical sectional view taken on the dotted line $e-f$ of Fig. 5. Fig. 7 is a cross section taken on the dotted line $g-h$ of Fig. 6. Fig. 8 is an elevation view of one of the devices employed to engage the edge of the supporting body said device being shown attached to a side member, a part of which is shown.

Similar characters of reference denote similar parts.

The side members comprise each a plurality of parts adjustable lengthwise of each other, the number of parts employed and their length depending upon the size of the tray which it is desired to make. As shown in the drawings the tray illustrated has side members comprising each 9 parts. For strength and lightness these parts comprise preferably channel formed parts slidably lengthwise one in the other, releasable means being provided for holding the parts against lengthwise movement. The parts comprising the side members are preferably made in three sizes. In the apparatus illustrated, there are in each side member, which as a whole is denoted by A, two horizontal channel formed parts 1 having slidably mounted in its ends two channel formed parts 2, in each of which is slidably mounted a similarly formed part 3. The middle part 3 has its ends slidably mounted in the two adjacent parts 2, the end parts 3 of each side member A being connected, preferably by hinges C, to the adjacent ends of the end members B. The parts 1, 2 and 3 are disposed with the channels on the inner sides, preferably, the bottom of the channel of each part being vertically disposed. The inner edges of the horizontal portions of each part 1, 2 and 3 are provided with vertical flanges 4 which extend toward each other. Each end member, B, in the form illustrated, comprises three parts 1, 2 and 3 corresponding in form and disposed relatively to each other the same as similar parts are disposed in the side members A, adjacent parts of the end members B being connected to adjacent parts of the side members A by hinges C which permit the parts to be collapsed as shown in Fig. 2.

100 To retain the members A and B at angles to each other, when the apparatus is in use, any suitable releasable locking means may be employed. In the drawings I have

shown two hooks D pivoted respectively to the parts 3 of the side members A, the free ends of such hooks being adapted to enter respectively eyes D' secured respectively on the 5 inner sides of the adjacent parts 3 of the members B.

The side and end members being extensible, it is desirable to have some means for releasably holding the parts of each member 10 in the position to which they may be adjusted. In the drawings I have illustrated resilient, yielding means for releasably holding the parts of members A and B against lengthwise movement relative to each other. A 15 plurality of spring wires E are secured at their middle portions one to the upper flange 4 of each part 2 of the side and end members A and B. Each spring wire E has its free ends turned at right angles outwardly and 20 then upwardly, as shown in Fig. 7. The ends of each flange 4 of each part 2 is provided with transverse holes 5 through which extend the free bent ends of the spring wire E which is mounted on such part 2. The 25 free ends of the wires E normally press upward on the lower edges of the upper flanges 4 of the adjacent parts 1 and 3 respectively, and thus resist lengthwise movement of the parts 1, 2 and 3 relative to each other. The 30 upper flanges 4 of the parts 1 and 3 are provided on their lower edges with downwardly extending projections 6 adapted to engage the adjacent bent ends of the wires E for preventing the parts 1, 2 and 3 being pulled 35 apart. The upper flanges of the parts 1 and the middle part 3 of each member A are provided each with two such projections 6, said projections being disposed adjacent the respective ends of such parts 1 and 3. The 40 end parts 3 of the members A and the parts 1 and 3 of the end members 3 are provided each with but one projection 6 on the upper flange 4, said projection, of course being located on the end of the part next adjacent 45 the part 2. The holes 5 are large enough so as to permit the ends of the spring wires E being depressed sufficiently to permit the turned ends of said wires to pass under the adjacent projections 6 on the flanges 4, when 50 it is desired to withdraw the parts 1, 2 and 3 from engagement with each other. Such holes 5 are preferably not vertically long enough to permit the upwardly turned ends of the wires E to pass out through the said 55 holes.

The side members A are provided with means for engaging the edges of the supporting body, such as a table, counter or show case denoted by F. These engaging 60 means are provided so that the apparatus may not accidentally be moved laterally on the table or counter. The preferable means for accomplishing this object comprise a plurality of buttons G preferably pivoted 65 at their upper ends to the outer sides of the

parts 1 of the members, the lower ends being adapted to be swung, as shown in Fig. 8 so as to extend below the upper surface of the supporting body F. When not in use the buttons G may be swung to a 70 horizontal position, as shown in dotted lines in Fig. 8. In Fig. 4 I have shown a preferable manner of pivoting the button G to its support. Within the channel of the part 1 is mounted a longitudinal block H, 75 which is provided with a horizontal hole in which is mounted a rivet I which also extends through the button G and a dished resilient washer J mounted on the outer side of the button G and held by the rivet I with 80 a spring pressure against the button. The friction of the spring washer J holds the button G in the position in which it may be disposed. Similar buttons G may be similarly secured to the outer sides of the parts 85 1 and 3 of each end member B, as shown in Figs. 1 and 5.

I provide extensible transverse partitions K having their ends connected preferably pivotally to opposite parts of the members 90 A. The partitions K are preferably constructed similarly to the end members B. No releasable means for holding the parts 1, 2 and 3 of the partitions K need be employed. Hinges L connect adjacent parts 95 of each partition K with the adjacent part of the two members A.

When it is desired to employ my invention in connection with a supporting body, such as a counter, the end members B, as 100 well as partitions K, are extended by pulling apart the sides A until the buttons G on the side members will pass the side edges of the counter, then the members A are forced toward each other until the buttons G engage opposite edges of the counter, as shown in Fig. 1. The end buttons G are turned as shown in Fig. 1, to the horizontal position. The end members B are then moved toward or from each other to the positions desired. 110

When it is desired to collapse the apparatus, it is removed from the supporting body F, the hooks D swung so as to be disengaged with the eyes D', after which the ends B and partitions K may be swung 115 parallel with the side members A, as shown in Fig. 2. In this form the apparatus is compact and may be stored or shipped readily.

As assembled and disposed as shown in 120 Fig. 1, the members A, B and partitions K form with the counter F a tray having a plurality of compartments for holding different articles, the ends B and sides A forming the sides of the tray, of which F forms the 125 bottom.

The extensible sides and ends permit my device to be easily fitted for use with supporting bodies of different dimensions, and the compact form into which it can be col- 130

lapsed when not in use renders the apparatus very desirable.

My invention may be modified in different ways within the scope of the appended 5 claims without departing from its spirit.

Having thus described my invention, what I claim and desire to secure by Letters Patent, is:—

1. The combination with extensible side 10 members, of end members hinged respectively to the side members and coöperating therewith to form the sides of a tray, and a transverse partition hinged at its ends to the two side members respectively.

15 2. The combination with extensible side members, of extensible end members hinged respectively to the side members and coöperating therewith to form the sides of a tray, and a transverse partition also extensible 20 and hinged at its ends to the side members respectively.

25 3. The combination with side and end members each extensible and hinged to each other to form the sides of a tray, of releasable means for locking the end and side members at angles to each other, and an extensible partition hinged at its ends to the side members respectively.

30 4. The combination with extensible side and end members hinged to each other to form the sides of a tray, of means for releasably holding said members against length-

wise movement, and an extensible partition hinged at its ends to the side members respectively.

35

5. The combination with extensible side and end members hinged to each other to form the sides of a tray, of releasable means for holding each member from extension, releasable means for holding the end and side 40 members at angles to each other, and an extensible partition hinged at its ends to the side members respectively.

6. The combination with extensible side and end members comprising each member 45 a plurality of parts slidabie one in the other lengthwise, of resilient means for releasably holding the parts of each member from lengthwise movement, the side and end members being hinged respectively to each other 50 to form the sides of a tray, releasable means for locking the side and end members at angles to each other, and the side members having downwardly extending means for engaging the edges of a supporting body, and an 55 extensible partition hinged at its ends to the side members respectively.

In testimony whereof I have signed my name to this specification in the presence of two subscribing witnesses.

JULIUS J. KARGES.
